UNITED STATES PATENT OFFICE

ARVID W. JOHNSON, OF LOS ANGELES, CALIFORNIA

DISPLAY DEVICE

Application filed December 1, 1927. Serial No. 236,965.

This invention relates to a device for intermittently and progressively displaying panels having printed or like display matter thereon. It is especially serviceable for 5 the display of advertising matter and the embodiment of the invention described and illustrated herein is such an advertising display device.

The objects of the present invention are to 10 provide a web formed of panels each having display matter, rolls for the web which alternately act as magazine and take-up rolls; mechanism for causing the web to travel between the rolls, stop with a panel in display 15 position and then travel to position the next panel for display and repeat the cycle of operation, and upon the termination of the travel of the web from one roll to the other to automatically reverse the direction of 20 travel. Further objects of this invention are to provide a transmission mechanism for intermittently actuating driven members; and still further objects of this invention are to 25 provide a transmission mechanism of the character described which alternately operates driven members at the ends of their travel.

Other objects and advantages will be made 30 fully apparent from the following specification in connection with the accompanying drawing, in which:

Fig. 1 is a rear elevation of the mechanism; Figs. 2, 3, 4 and 5 are views as seen on the lines correspondingly numbered in Fig. 1; Fig. 6 35 is a section as seen on the line 6-6 of Fig. 2; Fig. 7 is a perspective view of the trip mechanism; Fig. 8 is a section as seen on the line 8-8 of Fig. 4; Fig. 9 is a rear elevation of the clutch mechanism; and Fig. 10 is a side 40 elevation of the clutch and trip mechanism.

Referring more particularly to the drawing, a rectangular frame is indicated by 10. This frame is of such a character as to carry the various elements of the mechanism, so 45 that it may be housed within a case with a window. The case and window not being a part of the present invention are not illustrated. At the ends of the frame are rolls 11 and 12 mounted upon shafts to which they 50 are secured. These shafts indicated by 13

and 14 are for the purpose of driving the rolls and are journaled in the frame. The rolls are similar in construction, each having a bevel gear secured thereto indicated respectively by the reference numerals 15 and 16. 55 To the end of shaft 13 is secured a bevel pinion 17. The rolls are arranged to have secured thereto a flexible web 18 whereby the web may be wound upon one roll and unwound from the other. To hold the web in position 60 for suitably displaying the matter thereon idler rollers are mounted in the frame. One of these rollers is indicated by 19 in Figs. 2 and 10. There is a corresponding roller, not shown, adjacent roll 12. The web consists of 65 a number of panels having display matter thereon, these panels being connected together by suitable clips 20, see Figs. 2 and 10, which clips provide trip members, such clips being at the ends of each panel. 70

Mounted upon the frame upon a suitable bracket is an electric motor 21 which serves as a prime mover for operating the mechanism. A shaft 22 is operated thereby, and secured to the shaft is a worm 23. In mesh 75 with the worm is a worm wheel 24. The worm wheel 24 is keyed to a shaft 25 which extends between the rolls.

There are two transmission mechanisms one for each roll, one being indicated generally 80 by A and the other by B. As these mechanisms are substantially the same in construction, only one will be described. Rotatably, mounted upon the shaft 25 at the end is a bevel pinion 26 which meshes with the bevel 85 gear 15. A similar bevel pinion for the other transmission is mounted on shaft 25 and meshes with bevel gear 16. Bevel pinion 26 has a clutch element 27 geared thereto including clutch teeth. Splined upon the shaft 25 90 so as to be longitudinally movable, but rotatable therewith is an intermediate clutch element 28 having jaws on opposite sides, one set of jaws being for the teeth of clutch 27. The intermediate clutch element 28 has 95 an annular groove for rollers 30 on a keeper yoke 31. Yoke 31 is forked and it is suitably mounted intermediate its ends upon a pivot shaft 32. A tension spring 33 is secured to the casing housing the gears tending to hold 100

the keeper with the intermediate clutch element out of engagement with the roll clutch element 27. The other end of the keeper yoke serves as a blade for a two point electric switch which may control lights for illuminating the display matter at the proper time. However, this forms no part of the present invention and will not be further described. Freely movable upon the shaft 25 so as to be rotatable and longitudinally movable is a clutch element 34 for operating a cam. A worm sleeve 35 is rotatably mounted upon shaft 25. There are slots in the upper end of sleeve 35 to receive projections 36 on the cam clutch element 34, whereby to keep the sleeve and cam clutch element rotatably secured to one another and permit longitudinal movement of the cam clutch element. Meshing with the worm 35 on the worm sleeve is a worm wheel 37 fixed to a shaft 38. Fixed to the shaft 38 is a cam wheel 39 arranged to lift a follower 40. At the top of the follower is a forked arm 41 engaging the shoulder beneath a flange on the cam clutch element 34. A leaf spring 42 secured to the casing and pressing downwardly on the flange 41 tends to hold the cam clutch element in its lower position.

Extending from the side of one leg of the yoke 31 is a pin 43 arranged to be engaged by a hook on a latch 44. Latch 44 is pivotally mounted upon the frame so as to engage the pin 43. A trigger 45 is disposed in the slot of an actuator 46. The latter has an angularly disposed arm 48 with a roller 49 at the end thereof for riding over the trips 20 on the panels. A supporting member 50 on the frame is disposed on the other side of the web to hold the latter against movement as the roller 49 rides thereover. A leaf spring 51 is mounted at one end upon the housing for the mechanism and pressing against the arm 48 tends to hold the roller 49 against the web. A trip riding under the roller will rock the actuator and thereby rock the trigger 44 to disengage it from pin 43.

When the parts are in a position shown in Fig. 2, intermediate clutch element 28 is in engagement with the cam clutch element 34. Rotation of shaft 25 will cause the worm sleeve to be rotated. This causes the cam 39 to be rotated. The cam is initially in a position shown in Fig. 6. As the cam rotates one of its points engages the roller on the lower end of follower stem 40, and raises the follower against the action of spring 42. This causes cam clutch 34 to be raised to engage the intermediate clutch element and the latter to be raised until it eventually is engaged with the roll clutch element 27. At the upper end of the movement of intermediate clutch element 28, the points of the cam 39 ride from below the follower 40 and release the latter. Spring 42 then returns the cam clutch element to its lower position out

of engagement with the intermediate clutch element. The intermediate clutch element is retained in its upper position, by reason of the trigger 44 holding the pin 43. There will have been an initial rotation of the bevel gear 26 and the roll 11, causing the web to be wound upon the roll and moving the clips 20 beyond the roller 49 on the actuator. In the position last attained, the worm sleeve ceases 35 to rotate, while the roll continues to rotate. The web will continue to be wound upon roll 11 until the next set of clips ride beneath the roller on actuating arm 48. As the clips pass under the actuating arm, the latter is moved swinging the trigger 44 so as to release pin 43 and permit the tension spring 33 to swing the keeper yoke 31 downwardly and the intermediate clutch element out of engagement with the roll clutch element. The roll clutch element then ceases to operate and the web remains stationary with the panel displayed. However, worm sleeve 35 is now clutched to the shaft 25 by reason of the intermediate clutch element 28 engaging clutch element 34, and rotation of the cam wheel 39 begins, again raising the follower 40, the cam clutch element and the intermediate clutch element, until the intermediate clutch element again engages the roll clutch element starting rotation of the latter. The cam wheel 39 has now moved to the position such that the follower 40 is moved downwardly by the spring 42, disengaging the worm sleeve from the shaft 25, whereby the cycle of operation is again passed through.

The three element clutch effects intermittent operation or travel of the web, until the roll 11 has wound the entire web upon it. When this occurs, the roll is disconnected from the shaft and the transmission unit A becomes inoperative, while the transmission unit B is placed in operation to turn roll 11. This is effected by the following mechanism: Journalled upon the frame at one side is a threaded shaft 52. At the upper end thereof is a bevel pinion 53 meshing with the bevel pinion 17. Mounted upon the threaded shaft is an internally threaded collar 54 having a forked tappet 55 embracing a shiftable rod 56. Pivotally mounted upon the frame are bell crank levers 57 and 58 similar in construction. A catch arm 59 on bell crank lever 57 is arranged to register with a lug 60 on the yoke 31 in one position of the arm and to be out of registration in another position. The catch levers 57 and 58 are connected to the shiftable rod 56 so that when one of the levers registers with its corresponding lug on a yoke, the other will be out of registration. The catch arm 59 is made of such length that when it is registered with its lug 60, the yoke will be positioned with its intermediate clutch element in neutral position or out of engagement with both clutch elements 27 and 33. Adjustably mounted by

means of clutch screw upon the shiftable rod are abutments 61 and 62. These abutments are arranged to be engaged by the tappet 55. The abutments are properly positioned by trial so that when the entire web has been wound upon roll 11, abutment 62 will have been engaged by tappet 55 and the rod shifted downwardly so as to swing catch 57 into engagement with the lug on yoke 31, permitting the yoke to be moved by spring 33 to neutral position while catch will be swung to disengage the arm from the lug on its yoke for transmission unit B, releasing the intermediate clutch at that end, and locking the intermediate clutch in central position at its upper end. Transmission unit B now operates.

What I claim is:—

1. A display machine comprising a web divided into panels having display matter thereon, rolls between which said web travels, it being wound upon one roll and unwound from the other; a transmission mechanism including three aligned clutch elements normally out of clutching engagement, gearing connecting the first clutch element and a roll, a shaft, a prime mover for said shaft, the intermediate clutch element being connected to rotate with said shaft and being longitudinally movable on said shaft, the third clutch element being longitudinally movable to engage said intermediate clutch element and actuate the latter to engage said first clutch element, keeper means to longitudinally move said intermediate clutch element, said keeper means tending to move said intermediate clutch element out of engagement with said first clutch element and into engagement with said third clutch element, a trigger to hold said keeper means in position with said intermediate and first clutch elements in clutch engaging position, means to trip said trigger actuated by said web at the end of travel of a panel, and cam means operated by rotation of said third clutch element to move said third clutch element into engagement with said intermediate clutch element and the latter into engagement with said first clutch element.

2. A display machine comprising a web divided into panels having display matter thereon, rolls between which said web travels, it being wound upon one roll and unwound from the other; a shaft, a prime mover for said shaft, a pair of transmission mechanisms one for each roll, each transmission mechanism including three aligned clutch elements normally out of clutching engagement, gearing connecting the first clutch element and a roll, the intermediate clutch element being connected to rotate with said shaft and longitudinally movable on said shaft, the third clutch element being longitudinally movable to engage said intermediate clutch element and actuate the latter to engage the first clutch element, keeper means to longitudinally move said intermediate clutch element, said keeper means tending to move said intermediate clutch element out of engagement with said first clutch element and into engagement with said third clutch element, a trigger to hold said keeper means in position with said intermediate and first clutch elements in clutch engaging position, means to trip said trigger actuated by said web at the end of travel of a panel, cam means operated by rotation of said third clutch element to move said third clutch element into engagement with said intermediate clutch element and the latter into engagement with said first clutch element; catches, one for each keeper means to retain the latter in neutral clutch disengaging position, a screw driven by said prime mover, a collar threaded on said screw so as to be moved longitudinally thereon, said collar having a tappet, a longitudinally shiftable rod for actuating said catches to position one catch in retaining position and the other in releasing position, abutments on said rod disposed to be engaged alternately by said

first clutch element, keeper means to longitudinally move said intermediate clutch element, said keeper means tending to move said intermediate clutch element out of engagement with said first clutch element and into engagement with said third clutch element, a trigger to hold said keeper means in position with said intermediate and first clutch elements in clutch engaging position, means to trip said trigger actuated by said web at the end of travel of a panel, cam means operated by rotation of said third clutch element to move said third clutch element into engagement with said intermediate clutch element and the latter into engagement with said first clutch element; catches one for each keeper means to retain the latter in neutral clutch disengaging position, means operated by said prime mover proportionately to the travel of said web to alternately move at the ends of travel of web one catch into retaining position and the other into releasing position whereby to reverse the travel of said web.

3. A display machine comprising a web divided into panels having display matter thereon, rolls between which said web travels, it being wound upon one roll and unwound from the other; a shaft, a prime mover for said shaft, a pair of transmission mechanisms, one for each roll, each transmission mechanism including three aligned clutch elements normally out of clutching engagement, gearing connecting the first clutch element and a roll, the intermediate clutch element being connected to rotate with said shaft and longitudinally movable on said shaft, the third clutch element being longitudinally movable to engage said intermediate clutch element and actuate the latter to engage the first clutch element, keeper means to longitudinally move said intermediate clutch element, said keeper means tending to move said intermediate clutch element out of engagement with said first clutch element and into engagement with said third clutch element, a trigger to hold said keeper means in position with said intermediate and first clutch elements in clutch engaging position, means to trip said trigger actuated by said web at the end of travel of a panel, and cam means operated by rotation of said third clutch element to move said third clutch element into engagement with said intermediate clutch element and the latter into engagement with said first clutch element; catches, one for each keeper means to retain the latter in neutral clutch disengaging position, a screw driven by said prime mover, a collar threaded on said screw so as to be moved longitudinally thereon, said collar having a tappet, a longitudinally shiftable rod for actuating said catches to position one catch in retaining position and the other in releasing position, abutments on said rod disposed to be engaged alternately by said

tappet at the ends of travel of said web whereby to reverse travel of said web.

4. A display machine comprising a web divided into panels having display matter thereon, trips located at each panel, rolls between which said web travels, it being wound upon one roll and unwound from the other; a transmission including a roll clutch element, gearing connecting said roll clutch element and a roll for effecting rotation of the latter, an intermediate clutch element normally disposed out of engagement with said roll clutch element, a prime mover, gearing connecting said prime mover and said intermediate clutch element to rotate the latter, a cam clutch element normally out of engagement with said intermediate clutch element, keeper means to longitudinally move said intermediate clutch element, said keeper means tending to move said intermediate clutch element out of engagement with said roll clutch element and into engagement with said cam clutch element, a trigger for said keeper means to hold the latter in position with said intermediate and roll clutch elements in clutch engaging position, an actuator operated by said trips to actuate said trigger so as to release said keeper means, a cam mechanism for moving said cam clutch element to clutch said three clutch elements together, and gearing to actuate said cam mechanism upon engagement of the intermediate clutch element and said cam clutch element.

5. A display machine comprising a web divided into panels having display matter thereon, trips located at each panel, rolls between which said web travels, it being wound upon one roll and unwound from the other; a prime mover; a pair of transmission mechanisms, one for each roll, each transmission mechanism including a roll clutch element, gearing connecting each of said roll clutch elements and a corresponding roll for effecting rotation of the latter, an intermediate clutch element normally disposed out of engagement with said roll clutch element, gearing connecting said prime mover and said intermediate clutch element to rotate the latter, a cam clutch element normally out of engagement with said intermediate clutch element, keeper means to longitudinally move said intermediate clutch element said keeper means tending to move said intermediate clutch element out of engagement with said roll clutch element and into engagement with said cam clutch element, a trigger for said keeper means to hold the latter in position with said intermediate and roll clutch elements in clutch engaging position, an actuator operated by said trips to actuate said trigger so as to release said keeper means, a cam mechanism for moving said cam clutch element to clutch said three elements together, gearing to actuate said cam mechanism upon engagement of the intermediate clutch element and said cam clutch element;

10 15 20 25 30 35 40 45 50 55 60 65 70 75 80 85 90 95 100 105 110 115 120 125 130

6. A display machine comprising a web divided into panels having display matter thereon, trips located at each panel, rolls between which said web travels, it being wound upon one roll and unwound from the other; a prime mover, a pair of transmission mechanisms, one for each roll, each mechanism including a roll clutch element, gearing connecting each of said roll clutch elements and its corresponding roll for effecting rotation of the latter, an intermediate clutch element normally disposed out of engagement with said roll clutch element, gearing connecting said prime mover and said intermediate clutch element to rotate the latter, a cam clutch element normally out of engagement with said intermediate clutch element, keeper means to longitudinally move said intermediate clutch element said keeper means tending to move said intermediate clutch element out of engagement with said roll clutch element and into engagement with said cam clutch element, a trigger for said keeper means to hold the latter in position with said intermediate and roll clutch elements in clutch engaging position, an actuator operated by said trips to actuate said trigger so as to release said keeper means, a cam mechanism for moving said cam clutch element to clutch said three elements together, gearing to actuate said cam mechanism upon engagement of the intermediate clutch element and said cam clutch element; catches, one for each intermediate clutch element to retain its keeper means in clutch disengaging position, a screw driven by said prime mover, a collar thereon, said collar having a tappet, a longitudinally shiftable rod for actuating said catches to position one in retaining position and the other in releasing position, abutments on said rod disposed to be engaged alternately by said tappet at the ends of travel of said web whereby to reverse travel of said web.

7. A display machine comprising a web divided into panels having display matter thereon, trips located at each panel, rolls between which said web travels, it being wound upon one roll and unwound from the other, a transmission mechanism including a prime mover, a shaft rotated thereby, a roll clutch element freely rotatable on said shaft, gearing connecting said roll clutch element and a roll for effecting rotation of the latter, an intermediate clutch element normally disposed out of engagement with said roll clutch

clutch element and said cam clutch element; catches one for each intermediate clutch element to retain its keeper means in neutral clutch disengaging position, means operated by said prime mover proportionately to the travel of said web to alternately move at the ends of travel of said web one catch into retaining position and the other into releasing position whereby to reverse travel of said web.

75 80 85 90 95 100 105 110 115 120 125 130

8. A display machine comprising a web divided into panels having display matter thereon, trips located at each panel, rolls between which said web travels, it being wound upon one roll and unwound from the other; a prime mover, a pair of transmission mechanisms, one for each roll, each mechanism including a roll clutch element, gearing connecting each of said roll clutch elements and its corresponding roll for effecting rotation of the latter, an intermediate clutch element normally disposed out of engagement with said roll clutch element, gearing connecting said prime mover and said intermediate clutch element to rotate the latter, a cam clutch element normally out of engagement with said intermediate clutch element, keeper means to longitudinally move said intermediate clutch element said keeper means tending to move said intermediate clutch element out of engagement with said roll clutch element and into engagement with said cam clutch element, a trigger for said keeper means to hold the latter in position with said intermediate and roll clutch elements in clutch engaging position, an actuator operated by said trips to actuate said trigger so as to release said keeper means, a cam mechanism for moving said cam clutch element to clutch said three elements together, gearing to actuate said cam mechanism upon engagement of the intermediate clutch element and said cam clutch element; catches, one for each intermediate clutch element to retain its keeper means in clutch disengaging position, a screw driven by said prime mover, a collar thereon, said collar having a tappet, a longitudinally shiftable rod for actuating said catches to position one in retaining position and the other in releasing position, abutments on said rod disposed to be engaged alternately by said tappet at the ends of travel of said web whereby to reverse travel of said web.

9. A display machine comprising a web divided into panels having display matter thereon, trips located at each panel, rolls between which said web travels, it being wound upon one roll and unwound from the other, a transmission mechanism including a prime mover, a shaft rotated thereby, a roll clutch element freely rotatable on said shaft, gearing connecting said roll clutch element and a roll for effecting rotation of the latter, an intermediate clutch element normally disposed out of engagement with said roll clutch

- element and splined to said shaft, a cam clutch element normally out of engagement with said intermediate clutch element and freely movable longitudinally and rotatably on said shaft, keeper means to longitudinally move said intermediate clutch element, said keeper means tending to move said intermediate clutch element out of engagement with said roll clutch element and into engagement with said cam clutch element, a trigger for said keeper means to hold the latter in position with said intermediate and roll clutch elements in clutch engaging position, an actuator operated by said trips to actuate said trigger so as to release said keeper means, a cam mechanism for moving said cam clutch element longitudinally to clutch said elements together, and gearing to actuate said cam mechanism upon engagement of the intermediate clutch element and said cam clutch element.
8. A display machine comprising a web divided into panels having display matter thereon, trips located at each panel, rolls between which said web travels, it being wound upon one roll and unwound from the other; a shaft, a prime mover for said shaft, a pair of transmission mechanisms, one for each roll, each transmission mechanism including a roll clutch element rotatable on said shaft, gearing connecting said roll clutch element and its corresponding roll for effecting rotation of the latter, an intermediate clutch element normally disposed out of engagement with said roll clutch element and splined to said shaft, a cam clutch element normally out of engagement with said intermediate clutch element and freely movably longitudinally and rotatably on said shaft, keeper means to longitudinally move said intermediate clutch element, said keeper means tending to move said intermediate clutch element out of engagement with said roll clutch element and into engagement with said cam clutch element, a trigger for said keeper means to hold the latter in position with said intermediate and roll clutch elements in clutch engaging position, an actuator operated by said trips to actuate said trigger so as to release said keeper means, a cam mechanism for moving said cam clutch element longitudinally to clutch said three clutch elements together, gearing to actuate said cam mechanism upon engagement of the intermediate clutch element and said cam clutch element; catches, one for each intermediate clutch element to retain its keeper means in neutral clutch disengaging position, a screw driven by said prime mover, a collar threaded on said screw so as to be moved longitudinally thereon, said collar having a tappet, a longitudinally shiftable rod for actuating said catches to position one in retaining position and the other in releasing position, abutments on said rod disposed to be engaged alternately by said tappet at the ends of travel of said web whereby to reverse the travel of said web.
10. A display machine comprising a web divided into panels having display matter thereon, trips located at each panel, rolls between which said web travels, it being wound upon one roll and unwound from the other; a transmission including a prime mover, a shaft operated thereby, a roll clutch element rotatable on said shaft, gearing connecting said roll clutch element and a roll for effecting rotation of the latter, and intermediate clutch element normally disposed out of engagement with said roll clutch element and splined to said shaft, a cam clutch element normally out of engagement with said intermediate clutch element and freely movable longitudinally and rotatably on said shaft, keeper means to longitudinally move said intermediate clutch ele-
- 5 10 15 20 25 30 35 40 45 50 55 60 65 70 75 80 85 90 95 100 105 110 115 120 125 130

- ment said keeper means tending to move said intermediate clutch element out of engagement with said roll clutch element and into engagement with said cam clutch element, a trigger for said keeper means to hold the latter in position with said intermediate and roll clutch elements in clutch engaging position, an actuator operated by said trips to actuate said trigger so as to release said keeper means, a cam mechanism including a cam, a follower movable thereby to move said cam clutch element, gearing to actuate said cam mechanism upon engagement of said intermediate clutch and said cam clutch elements including a worm sleeve mounted for rotation on said shaft and having said cam clutch element secured thereto, and a worm wheel meshing with said worm sleeve for rotating said cam.
11. A display machine comprising a web divided into panels having display matter thereon, trips located at each panel, rolls between which said web travels, it being wound upon one roll and unwound from the other; a shaft, a prime mover for said shaft, a pair of transmission mechanisms, one for each roll, each transmission mechanism including a roll clutch element rotatable on said shaft, gearing connecting said roll clutch element and a roll for effecting rotation of the latter, an intermediate clutch element normally disposed out of engagement with said roll clutch element and splined to said shaft, a cam clutch element normally out of engagement with said intermediate clutch element and freely movable longitudinally and rotatably on said shaft, keeper means to longitudinally move said intermediate clutch element, said keeper means tending to move said intermediate clutch element out of engagement with said roll clutch element and into engagement with said cam clutch element, a trigger for said keeper means to hold the latter in position with said intermediate and roll clutch elements in clutch engaging position, an actuator operated by said trips to actuate said trigger so as to release said keeper means, a cam mechanism including a cam, a follower movable thereby to move said cam clutch element, gearing to actuate said cam mechanism upon engagement of the intermediate clutch element and said cam clutch elements including a worm sleeve mounted for rotation on said shaft and having said cam clutch element secured thereto, a worm wheel meshing with said worm sleeve for rotating said cam; catches one for each intermediate clutch element to retain its keeper means in clutch disengaging position, a screw driven by said prime mover, a collar threaded on said screw so as to be moved longitudinally thereon, said collar threaded on said screw so as to be moved longitudinally thereon, said collar having a tappet, a longitudinally shiftable rod for actuating said catches to position one in retaining position and the other in releasing position, abutments on said rod disposed to be engaged alternately by said tappet at the ends of the travel of said web whereby to reverse travel of said web.
12. A display machine comprising a web divided into panels having display matter thereon, trips located at each panel, rolls between which said web travels, it being wound upon one roll and unwound from the other; a shaft, a prime mover for said shaft, a pair of transmission mechanisms, one for each roll, each transmission mechanism including a roll clutch element rotatable on said shaft, gearing connecting said roll clutch element and a roll for effecting rotation of the latter, an intermediate clutch element normally disposed out of engagement with said roll clutch element and splined to said shaft, a cam clutch element normally out of engagement with said intermediate clutch element and freely movable longitudinally and rotatably on said shaft, keeper means to longitudinally move said intermediate clutch element, said keeper means tending to move said intermediate clutch element out of engagement with said roll clutch element and into engagement with said cam clutch element, a trigger for said keeper means to hold the latter in position with said intermediate and roll clutch elements in clutch engaging position, an actuator operated by said trips to actuate said trigger so as to release said keeper means, a cam mechanism including a cam, a follower movable thereby to move said cam clutch element, gearing to actuate said cam mechanism upon engagement of the intermediate clutch element and said cam clutch elements including a worm sleeve mounted for rotation on said shaft and having said cam clutch element secured thereto, a worm wheel meshing with said worm sleeve for rotating said cam; catches one for each intermediate clutch element to retain its keeper means in clutch disengaging position, a screw driven by said prime mover, a collar threaded on said screw so as to be moved longitudinally thereon, said collar threaded on said screw so as to be moved longitudinally thereon, said collar having a tappet, a longitudinally shiftable rod for actuating said catches to position one in retaining position and the other in releasing position, abutments on said rod disposed to be engaged alternately by said tappet at the ends of the travel of said web whereby to reverse travel of said web.
13. A transmission including a first clutch element, a driven member, trips on said driven member, gearing connecting said first clutch element and said driven member, an intermediate clutch element normally disposed out of engagement with said first clutch element, driving means for said intermediate clutch element to rotate the latter, a cam clutch element normally out of engagement with said intermediate clutch element, keeper means for longitudinally moving said intermediate clutch element, said keeper means tending to move said in-

termideate clutch element out of engagement with said first clutch element and into engagement with said cam clutch element, a trigger for said keeper means to hold the latter in position with said intermediate and first clutch elements in clutch engaging position, an actuator operated by said trips to actuate said trigger so as to release said keeper means, a cam mechanism for moving said cam clutch element to clutch said three elements together, and gearing to actuate said cam mechanism upon engagement of said intermediate clutch element and said cam clutch element.

15 In witness that I claim the foregoing I have hereunto subscribed my name this 18th day of November, 1927.

ARVID W. JOHNSON.
